UNITED STATES PATENT OFFICE.

ROMULUS R. RICHMOND, DECEASED, LATE OF OMAHA, NEBRASKA; BY MARY A. SHELTON, ADMINISTRATRIX, OF OMAHA, NEBRASKA, ASSIGNOR OF ONE-HALF TO HERBERT D. COOK AND ALEXANDER BURRELL, BOTH OF OMAHA, NEBRASKA.

GRAIN SHOCKER.

Application filed June 25, 1923. Serial No. 647,672.

This invention relates to improvements in grain shockers and has for its prime object to provide a shocker adapted to be coupled to a binder in any suitable way for moving 5 and operating the shocker as the binder is drawn or propelled over a field.

A further object of the invention is to provide a grain shocker adapted to receive a predetermined number of bundles and to 10 automatically discharge the bundles when same have reached the predetermined number.

A still further object of the invention is to provide a grain shocker which will automatically discharge the bundles from the 15 machine and stack them on the ground as loosely as if set up by hand, and which will permit the bundles to adjust themselves, thus preventing the stack from falling 20 or blowing over.

And a still further object of my invention is to provide a grain shocker which can be moved by the same power used for operating the binder, but one that dose not receive 25 its power from the binder.

Another object of the invention is to provide a grain shocker of the above indicated character, which is simple in construction, durable, efficient for the purpose intended, 30 and one that can be manufactured and placed on sale at a relatively low cost.

These and like objects of the invention will be better understood as the description follows and as is specifically pointed out in 35 the appended claims.

Referring to the accompanying drawings which form a part of this specification,

Figure 1 is a top plan view of a grain shocker constructed in accordance with my 40 invention.

Figure 2 is a side elevation of same.

Figure 3 is a vertical section taken on line 3—3 of Figure 1.

Figure 4 is an enlarged perspective view 45 of the operating mechanism, and

Figure 5 is a fragmentary section taken on line 5—5 of Figure 1.

Referring to the accompanying drawings in detail, like characters will be used to 50 designate like parts in the different views.

In the drawings, the numeral 1 indicates a U-shaped frame on which are journaled axles 2 for ground wheels 3. One side of

the U-shaped frame has an extension 4 attached thereto. Cross braces 5, 6, and 7 are 55 employed for supporting in a parallel plane with the U-shaped frame a brace member 8.

A bundle carrier 9 is pivotally supported on uprights 10 which are attached to the inner sides of the U-shaped frame 1. The 60 bundle carrier is so mounted on the supports 10 that the greater portion of the weight of the carrier is to the front of the supports, so that the carrier will automatically adjust itself upon discharging the 65 bundles therefrom, and assume the position indicated by full lines in Figure 2 of the accompanying drawings.

The U-shaped frame supporting the carrier 9 and ground wheels 3 is attached to a 70 binder (not shown) in any suitable manner, so that the bundles as indicated by the letter A when discharged from the binder are thrown onto a fork receiving rack 11 which is mounted for swinging movement on a rod 75 12, which is in turn journaled in bearings or upright supports 13 which are three in number and are connected to the brace 8.

A shaft 14 is journaled in bearings on the underside of the extension 4 and brace 8. 80 A sprocket 15 is keyed to the shaft 14 and is connected with a sprocket 16 on the axle 2 by a sprocket chain 17.

A beveled gear 18 is carried by one end of the shaft 14 and meshes with a beveled gear 85 19 keyed on a shaft 20 which is journaled in bearings 21 on the braces 5 and 6. Rings 22 and 23 respectively are keyed on opposite ends of the shaft 20 and each of the rings has an arm 24 formed integral therewith. 90 The arm 24 of the ring 22 is connected with a shaft 25, running parallel with the shaft 20 by means of pivotally connected links 26 and 27. The link 27 is connected to the shaft 25 through a link 28 which is provided with a lug 29. A sprocket 30 is keyed on one end of the shaft 25 and connected with a sprocket 31 on the shaft 12 by means of a sprocket chain 32.

A shaft 33 is journaled on the underside 100 and at the extreme end of the braces 5 and 6 and has a tendency to rotate in the direction of the shaft 25 by means of a coil spring 34, which connects the two shafts together.

A lever 35 is pivotally connected to the 105 link 26 and is provided with a notch 36

for engagement with the lug 29. The raising and lowering of the lever 35 is controlled by a U-shaped hook 37 secured on one end of the shaft 33. A second lever 38 having a notch 39 is pivotally connected as at 40 to the cross brace 6. The arm 24 of the ring 23 is connected to the end of the shaft 33 through a link 41 and an arm 42. The link 41 has a slot 43 therein for receiving a pin 44 carried by the arm 42. The shaft 14 has a ring 45 secured on one end and the ring is provided with an arm 46 which is pivotally connected at 47 to a link 48 which is provided with a slot 49. The free end of the link 48 is pivotally connected to an operating lever 50 intermediate its ends.

A shaft 51 journaled in the U-shaped frame 1 has a ring 52 secured rigidly thereto. The ring 52 has an arm 53 formed integral therewith and the arm is connected to the link 48 by a pin 54 that passes through the slot 49 and engages the end of the arm. One end of the operating lever is provided with a notched end 55 for engagement with the pin 54, the purpose of which will be better understood as the description follows.

Another shaft as indicated by the numeral 30 56 is supported in the U-shaped frame on a plane parallel with the shaft 51. A ratchet 57 is keyed to the shaft 56 and is rotated with the shaft by an operating pawl 58 pivotally carried by a lever 58^a. One end of the lever 58^a is pivoted on the shaft 56 so that said lever will turn thereon, while the opposite end thereof has an eye 58^b therein through which extends one end of a rod 59. The other end of the rod 59 is pivotally connected as at 60 to a crank arm 61 carried by one end of the shaft 12. A head 61^a on the rod 59 engages the lever 58^a to slightly turn the shaft 56 upon the turning movement of the shaft 12. To hold said ratchet 57 against retrograde movement, an arm 61^b having a pin 61^c thereon engaging the teeth of said ratchet is pivotally connected to the brace member 8.

A sprocket 62 is keyed to the shaft 51 adjacent each end and each of the sprockets are connected by sprocket chains 64' to a sprocket 63 carried by a stub-axle 64 on which the carrier 9 is supported in the standards 10.

As my improved grain shocker is being moved over the ground in connection with a binder, the bundles are delivered one at a time onto the forked frame 11. As the bundles are being delivered onto the forked frame, they strike against a pivoted control lever 65, the control lever being connected to the brace 6 by an L-shaped bracket 66. As the control lever swings on its pivot 67 one end strikes against the member 38 to move same upwardly permitting the lug 33'

formed integral on the shaft 33 to disengage the notched recess 39, and at the same time the spring 34 turns the shaft 33 whereby the U-shaped hook 37 allows the lever 35 to drop downwardly permitting the notched recess 36 to engage the lug 29. As the shaft 20 is kept constantly revolving through the gears 18, 19, sprockets 15, 16, and sprocket chain 17, it can be readily seen that the arm 24 of the ring 22 will cause the shaft 25 to 70 make a one-half turn and the sprocket 30 through the sprocket chain 32 operates a sprocket 68 on the shaft 12 to swing the forked frame 11 upwardly to discharge the bundles onto the carrier 9, after which the link 41 presses against the pin 44 of the arm 42 whereby the shaft 33 is partially rotated against the tension of the spring 34 to allow the notched recess 39 to engage the lug 33' on the shaft 33 and the U-shaped hook 37 85 raises the operating lever 35 disengaging the notched recess 36 from the lug 29, so that the forked frame returns to its original position ready for receiving another bundle.

The ratchet 57 is provided with ten teeth 90 and every time the forked frame 11 delivers a bundle onto the carrier 9, the shaft 56 is given one-tenth of a turn. When a total of ten bundles have been deposited on the carrier, a lug 69 on the said shaft engages the lever 50 which moves the notched end 55 into engagement with the pin 54 so that under the influence of the arm 46 the shaft 51 is turned, thus causing the sprockets 62, 63, and sprocket chains 64' to elevate the carrier 100 to the position shown by dotted lines in Figure 2, whereby the bundles are discharged onto the ground in stacks that easily adjust themselves to prevent falling or blowing over. During the dumping of the 105 bundles, the pawl 58 and pin 61^c are disengaged from the ratchet 57 by a lug 61^d rigidly carried by the shaft 56 engaging the arm 61^b which causes the pin 61^c to engage the pawl 58; so that the shaft 56 is 110 rotated under the influence of a spring 70 which permits the operating parts to assume the position indicated in Figure 4.

While I have shown and described the preferred form of my improved grain shocker, 115 I realize that various minor changes may be resorted to, without departing from the spirit and scope of the invention as claimed, and therefore, I do not wish to limit myself to the exact details of constructions shown, 120 nor to the combination and arrangement of parts.

What I claim as new and desire to secure by Letters Patent is:

1. In a grain shocker, comprising a U- 125 shaped frame, said frame being mounted on ground wheels, a bundle carrier mounted on said frame, a forked member pivoted at one side of said bundle carrier on said U-shaped frame, means for swinging said forked mem- 130

ber for discharging the bundles received thereon into the bundle carrier, means for holding said forked member against swinging movement, a control lever pivotally carried by said U-shaped frame for releasing said holding means to permit operation of said forked member, and means controlled by said swinging fork to discharge the bundles from said bundle carrier when a predetermined number of bundles have been deposited therein.

2. A grain shocker comprising a frame, ground wheels for supporting said frame, a bundle carrier pivotally mounted on said frame, a bundle fork pivotally mounted on the frame at one side of said bundle carrier, operating means driven by said ground wheels for swinging said forked member to discharge the bundles into said carrier, a control lever pivotally connected to said frame for controlling the operation of said bundle fork, and means for discharging the bundles from the carrier when a predetermined number have been deposited therein.

3. A grain shocker comprising a frame, a bundle carrier pivotally mounted on said frame, a shaft pivotally mounted at one side of said bundle carrier, a forked member affixed to said shaft, means for swinging said shaft to discharge bundles into said carrier, a crank arm on said shaft, a ratchet mechanism, a link connecting said crank arm and ratchet mechanism, and means operated by said ratchet mechanism for swinging said bundle carrier on its pivot when a predetermined number of bundles have been deposited therein.

4. A grain shocker comprising a frame, a bundle carrier pivotally mounted on said frame, a shaft pivotally mounted at one side of said bundle carrier, a forked member affixed to said shaft, means for swinging said shaft to discharge bundles into said carrier, a crank arm on said shaft, a ratchet mechanism, a link connecting said crank arm to said ratchet mechanism for operating same when said forked member is swung on its pivot, a second shaft operated by said ratchet mechanism, a projection on said second mentioned shaft, a power shaft, a crank arm on said power shaft, a link adapted to be reciprocated by said crank, a lever pivoted intermediate its ends on said link, said pivoted lever adapted to be engaged by said projection on said second mentioned shaft, and means adapted to be engaged by said lever when the same is engaged by said projection for connecting said power shaft to said bundle carrier for swinging the same on its pivot when a predetermined number of bundles have been deposited therein.

5. A grain shocker comprising a frame, a bundle carrier mounted on said frame, a forked member pivotally mounted on said

frame for discharging the bundles received thereon into said bundle carrier, power supply means for swinging said forked member on its pivot, said power supply means being normally in inoperative relation with said forked member, and means adapted to be engaged by the bundles when the same are deposited on said forked member for connecting said forked member with said power supply means.

6. A grain shocker comprising a frame, a bundle carrier mounted on said frame, a forked member pivotally mounted on said frame for discharging the bundles received thereon into said bundle carrier, power supply means for swinging said forked member on its pivot, a pivoted trip lever for holding said forked member in inoperative position with relation to said power supply means, and a lever adapted to be engaged by the bundles when deposited on said forked member for releasing said trip lever in order to connect said forked member with said power supply means.

7. A grain shocker comprising a frame, a bundle carrier mounted on said frame, a forked member pivotally mounted on said frame for discharging bundles received thereon into said bundle carrier, power supply means for swinging said forked member on its pivot, said power means being normally in inoperative relation with said forked member, a rotatable shaft, spring means for yieldably holding said shaft against turning movement, a pair of projections on said shaft, a trip lever having a notch therein adapted to receive one of said projections to hold said shaft against turning movement by said spring means, means adapted to be operated by the other projection on said shaft for connecting said power supply means with said forked member when said trip lever releases the projection received in the notch therein, and a lever adapted to be engaged by the bundles when deposited on said forked member for releasing said trip lever to connect the forked member with the power supply means.

8. A grain shocker comprising a frame, a bundle carrier mounted on said frame, a forked member pivotally mounted on said frame for discharging bundles received thereon into said bundle carrier, power supply means for swinging said forked member on its pivot, said power means being normally in inoperative relation with said forked member, a rotatable shaft, spring means for yieldably holding said shaft against turning movement, a pair of projections on said shaft, a trip lever having a notch therein adapted to receive one of said projections to hold said shaft against turning movement by said spring means, means adapted to be operated by the other projection on said shaft for connecting said power

supply means with said forked member when said trip lever releases the projection received in the notch therein, a lever adapted to be engaged by the bundles when deposited on said forked member for releasing said trip lever to connect the forked member with the power supply means, and means for

returning one of said projections into the notch in said trip lever after said forked member has been operated.

In testimony whereof, I have affixed my signature.

MARY A. SHELTON,
Administratrix.
